Patented Aug. 3, 1920.

FIG. 1.

FIG. 2.

By *Jesus J. Heap* Inventor
Shurtliff & Hess Attorneys

UNITED STATES PATENT OFFICE.

JESSE J. HEAP, OF NEW YORK, N. Y., ASSIGNOR TO UNION SPECIAL MACHINE COMPANY, OF CHICAGO, ILLINOIS, A CORPORATION OF ILLINOIS.

DOUBLE LAP-SEAM FOR SEWED ARTICLES.

1,348,645.

Specification of Letters Patent.

Patented Aug. 3, 1920.

Application filed November 8, 1918. Serial No. 261,649.

To all whom it may concern:

Be it known that I, JESSE J. HEAP, a citizen of the United States, residing at New York city, in the county of Kings, State of New York, have invented certain new and useful Improvements in Double Lap-Seams for Sewed Articles, of which the following is a description, reference being had to the accompanying drawing and to the figures of reference marked thereon.

The invention relates to new and useful improvements in lap seams for sewed articles, and more particularly to a double lap seam—that is, a seam wherein the edge 15 of each fabric section is folded in and the raw edges of the fabric are concealed by the seam.

An object of the invention is to provide a double lap seam of the above character, 20 wherein one of the fabric sections is provided with a reentrant fold back from its edge forming, in appearance, from the fabric section a tape, so that when the two fabric sections are joined by parallel lines of 25 stitches the seam has the appearance of being covered by a tape.

In the drawings which show by way of illustration one embodiment of the invention:—

30 Figure 1 is an enlarged sectional view through a seam embodying the invention; Fig. 2 is a perspective view of the same.

My improved double lap seam is formed by folding underneath one of the edges of 35 one fabric section and at a distance back from the edge forming a reentrant fold, so that there is formed in appearance a tape from the fabric section itself. The other section of the fabric is interfolded or left 40 straight and the two sections are secured together by parallel lines of stitches passing through the fabric sections adjacent the edges of the tape.

Referring more in detail to the drawings, 45 I have shown the two fabric sections at F and F'. The fabric section F has its edge folded back at 1. This same fabric section is also formed with a reentrant fold 2—that is, the fabric is folded to the right 50 and then to the left, as viewed in Figs. 1 and 2, and this forms from the section of the fabric a strip 3, which has the appearance of a separate tape. The under fabric section F', as shown in the drawings, is

folded back at 4. From certain aspects of 55 the invention, this lower section of fabric may be straight and without fold as it is on the wrong side of the seam. Parallel lines of stitches 5 and 6 are passed through the fabric sections adjacent the respective 60 edges of the strip 3. The stitches 5 pass through the reentrant fold 2 and through the folded edge 4 of the fabric section F' and serves to join the fabric sections and also secure the reentrant fold. The stitches 65 6 pass through the folded edge 1 of the fabric section F and through the fabric section F' and joins the two fabric sections.

It will thus be apparent that I have provided a lap seam for sewed articles which 70 includes two fabric sections, one of which has its edge folded and also has a reentrant fold back from the edge forming in appearance a tape, while the other section underlies the tape appearing part and the two sections are joined by the two parallel lines 75 of stitches adjacent the edges of the tape appearing part, which serve also to secure the reentrant fold.

It is obvious that minor changes in the 80 details of construction may be made without departing from the spirit of the invention, as set forth in the appended claims.

Having thus described my invention, what I claim as new and desire to secure by Letters Patent, is:—

1. A lap seam for sewed articles comprising two fabric sections, one of which has its edge folded and has a reentrant fold back from the edge forming from the fabric section in appearance a tape, said reentrant fold terminating at one side of and spaced from the folded edge, the other section underlying the folded edge and reentrant fold, and two parallel lines of stitches adjacent the 90 edges of the tape appearing part and passing through and joining the fabric sections, said lines of stitches being so located that one passes through and secures the reentrant fold and the other passes through and secures the folded edge.

2. A lap seam for sewed articles comprising two fabric sections, one of which has its edge folded and has a reentrant fold back from the edge forming from the fabric section in appearance a tape, the other section having its edge folded and underlying the tape appearing part, and two parallel lines 105

2
of stitches adjacent the edges of the tape appearing part and passing through and joining the fabric sections, one of said lines of stitches being so located as to pass through and secure the reentrant fold and also through and secure the fold in the underlying section of fabric.

In testimony whereof I affix my signature, in the presence of two witnesses.

JESSE J. HEAP.
